UNITED STATES PATENT OFFICE.

LEE DE FOREST, OF NEW YORK, N. Y.

WIRELESS-TELEGRAPH SYSTEM.

No. 824,003.

Specification of Letters Patent.

Patented June 19, 1906.

Application filed February 20, 1906. Serial No. 302,009.

To all whom it may concern:

Be it known that I, LEE DE FOREST, a citizen of the United States, and a resident of New York, in the county of New York and State of New York, have invented a new and useful Improvement in Wireless-Telegraph Systems, of which the following is a specification.

My invention relates to wireless-telegraph systems in which a closed oscillating circuit is coupled to an open oscillating or radiating circuit, and the object of my invention is to provide a coupled wireless-telegraph system whose natural mode of vibration shall be monoperiodic and which shall have a greater persistency of vibration than those now commonly employed.

As is now well understood, the resultant vibration produced by the natural oscillatory restoration to electrical equilibrium of a coupled system consisting of two circuits, both of which, when isolated, have the same natural period, is not, in general, monoperiodic, but is multiperiodic, consisting of at least two frequencies, neither one of which is equal to that natural to either of said circuits. Thus if the waves radiated by such a system be measured by a wave-meter, at least two wave lengths will be found, so that if a curve be plotted having as its ordinates the currents or potentials developed in the wave-meter circuit and as its abscissæ the progressively-varying values of the frequencies natural to said wave-meter circuit, at least two maxima of current or potential will be observed, and it will be found that the frequencies corresponding to said maxima are not the same as those natural to either of the component circuits of the coupled system. In wireless telegraphy such multiperiodic vibration renders accurate tuning impossible, for there are at least two frequencies and therefore a receiving-circuit can be attuned to either one of them; and also it renders transmission inefficient, for the radiated energy is distributed over, or divided between, waves of two frequencies instead of being concentrated into waves of one frequency. Therefore in order to render accurate tuning and efficient transmission possible it is necessary to employ a transmitting system which will develop electromagnetic waves of a single frequency, and a receiving system which will respond to waves of but a single frequency.

Various systems known as "loosely-coupled" systems have been devised for accomplishing the foregoing results but these, in general, depend upon loose magnetic linkage between the antenna and its associated transmitting or receiving circuit and, therefore, are unsuited for commercial long-distance working. However, I have discovered that by making the two paths from the top of an antenna to earth equal in period, the oscillations in a coupled system will have but a single frequency and the electromagnetic waves radiated by said system will be monoperiodic.

My invention therefore consists in making the aforesaid two paths from the top of the antenna to earth equal in period, so that the radiated waves will be monoperiodic, and also in eliminating the damping effect of the spark-gap, so that said waves and the oscillations creating them will have a greater persistency.

My invention may best be understood by having reference to the drawings which accompany and form a part of this specification and which show in diagrammatic form several systems of circuits embodying the principles of my invention.

In the drawings, Figures 1, 2, 3, 4, 5, 6, 7, 15 and 16 represent wireless-telegraph transmitting systems; Figs. 8, 9, 10, 11, 12, 13, 14, 17, 18, 19 and 20 represent wireless-telegraph receiving systems; and Figs. 21 and 22 are curves drawn to rectangular coördinates, in which the ordinates represent current amplitude and the abscissæ represent time, and which show, respectively, the modes of vibration of an oscillating circuit subject to the damping effect of a spark-gap and one not subject to such damping effect.

In the figures L , L_1 , L_2 , are inductances employed in the transmitting systems and L' , L'_1 , L'_2 , are the corresponding inductances in receiving systems, L'_1 is an inductance connected in one side of a receiving loop-antenna; C , C_1 , C_2 are condensers employed in the transmitting systems and C' , C'_1 , C'_2 are the corresponding condensers employed in the receiving systems; C_3 is a condenser employed to shunt the spark-gap of the transmitting oscillating circuit; C'_3 is a condenser employed to shunt the responder of the receiving oscillating circuit; A is a transmitting-antenna and A' is a receiving-antenna which, as shown, is a loop-antenna; R , R' are oscilla-

tion-responders; T, T' are telephones; B, B' are batteries; and P, P' are adjustable resistances.

In each of the figures, the electromagnetic constants of the antenna system and closed oscillating circuit are so chosen that the two paths from the top of the antenna to earth are equal in period. For this purpose said two paths may have equal capacity and equal inductance, or may have equivalent effective capacity and effective inductance, in both of which cases the product of the resultant capacity by the total inductance of one of said paths will be equal to the product of the resultant capacity by the total inductance of the other of said paths.

In Figs. 1, 2, 3, 4, 5, 6, 15 and 16 the fundamental natural period of the antenna system $A x, y E$ is made equal to that of the closed oscillating circuit conductively connected thereto at the points x and y . For example, in Fig. 1, the said antenna system has the same period as the circuit $x C L C_1 y C_2 L C$, in Fig. 2 it has the same period as the circuit $x C C_1 y C C$, in Fig. 3 it has the same period as the circuit $x C L C y C L C$, &c., and in all said figures the two paths from the top of the antenna to earth will have the same period as the conductively-connected oscillating circuits and the two components thereof included between the points x and y . In all of said figures, except Figs. 2 and 3, two sets of oscillations having different frequencies will be developed in the oscillating circuit so long as sparks pass across the gap S , for in each case there are two oscillating circuits of different natural periods employing the same spark-gap. However, in all said figures, including Figs. 2 and 3, the sparks cease to pass across the gap after one or two oscillations because the auxiliary shunt-path around the gap offers less opposition to the passage of oscillations than said gap, and thus the oscillating system passes almost instantly into a closed oscillating circuit which has no spark-gap or other discontinuity and which therefore has a far greater persistency than one which is metallically discontinuous. In all said figures, except Figs. 2 and 3, the period of the aforesaid closed oscillating circuit is different from that of either of the two circuits which vibrate before the spark-gap ceases to become conducting, and it is to the period of said closed oscillating circuit that the antenna system is attuned. For example, in Fig. 1, the circuit $S L C C L$ has a period different from that of the circuit $S C_1 C_2$, while the circuit $C L C_1 C_2 L C$ has a still different period and it is to this period that the period of the antenna system is made equal. In Fig. 2, however, the two circuits $S L_1 C C L_2$ are equiperiodic and in Fig. 3 the two circuits $S L C C L$ are equiperiodic, —hence in both figures there will be oscillations of but a single frequency so long as sparks pass across the

gap S . In Fig. 2, as soon as sparks cease to pass across the gap S , the oscillating circuit becomes the closed circuit $C C C C$ which is so constructed as to have the same period as that of the antenna system. However, in Fig. 3, the closed oscillating circuit $C L C C L$, formed when sparking ceases at the gap has the same natural period as either of the two circuits $S L C C L$, so that oscillations of but one frequency are developed in the system from the beginning to the end of the electrical movement.

The systems shown in Figs. 4, 5, 6, 15 and 16 are alike in principle to the system shown in Fig. 1 and their operation will be understood from the foregoing description. It will be noted that in each of said figures, as well as in Figs. 1, 2 and 3, an auxiliary shunt-path around the spark-gap is provided and that in Figs. 2 and 3 said shunt-path forms one of a pair of equiperiodic oscillating circuits. The inductance L , shown serially connected in the antenna system is for the purpose of increasing the natural period of the antenna system without at the same time altering the natural period of the closed oscillating system for the purpose of putting the two systems into syntony.

In Fig. 7, I have shown an extension of the systems above described in which the original oscillating circuit $S C_1 I_1 C_1$ is inductively related to the closed oscillating circuit $C I_2 I_3 C$ by the loose-linkage transformer M . The condenser C_3 forms an auxiliary shunt-path around the gap S , and as soon as sparking ceases at said gap oscillations of a single frequency are developed in the closed oscillating circuit $C_3 C_1 I_1 C_1$ and in the closed oscillating circuit $C I_2 I_3 C$ and hence in the antenna system. If said condenser C_3 be omitted, oscillations of a single frequency will be developed from the time of the initial discharge across said gap until the system regains its electrical equilibrium, but a greater persistency is gained by employing said condenser. In this case the closed oscillating circuits $C_3 C_1 I_1 C_1$ and $C I_2 I_3 C$ are equal in period and the antenna system is given the sound period as said circuits. Obviously the two paths to earth from the top of said antenna also will have the same period as said closed oscillating circuits.

Figs. 8, 9, 10, 11, 12, 13, 14, 17, 18, 19 and 20 show various forms of receiving-circuits corresponding to the transmitting-circuits above described and embodying the principles thereof. Said receiving-circuits may be connected between the points x', y' of loop receiving-antenna as shown or they may be connected to open-ended antennæ. In all cases, either with open-ended or loop antennæ, the electromagnetic constants of the system are so chosen that the two paths to earth E from the top of the antennæ z will be equal in period.

In Fig. 8, the responders R , R' , are connected in the two sides, respectively, of the closed oscillating circuit $C' L' R R' L' C'$ and each is provided with a telephone T , T' and associated battery B , B' , and variable resistance P , P' . One telephone may be held to each ear of the receiving operator, or as shown in Figs. 17 and 20, one telephone, which may be a head-telephone, may be employed and so connected as to receive current from both responders. In Fig. 17, the telephone T and battery B are connected in shunt across the circuit containing the serially-connected responders R , R' , and in Fig. 20, each responder is connected in series with a primary of a different one of the two transformers M_2 , M'_2 , whose secondaries are serially connected with the telephone T .

It will be noted that for each of the transmitting systems, there is a corresponding receiving system,—thus Fig. 8 corresponds to Fig. 1; Fig. 9 to Fig. 2; Fig. 10 to Fig. 3; Fig. 11 to Fig. 4; Fig. 12 to Fig. 5; Fig. 13 to Fig. 6; Fig. 18 to Fig. 7; Fig. 14 to Fig. 15; and Fig. 17 to Fig. 16; while Fig. 20 also corresponds to Fig. 1, showing an arrangement of signal-indicating apparatus different from that shown in Fig. 8, and Fig. 19 shows a modification of Fig. 18.

In all the receiving systems, the natural period of the closed oscillating circuit which is conductively connected between the points x' , y' to the antenna system is made equal to that of said antenna system, and in Figs. 18 and 19, in which the responder R is included in a secondary closed oscillating circuit inductively related to that which is conductively connected to the antenna system, the natural period of said secondary oscillating circuit also is made equal to that of the antenna system. It follows that as explained above in connection with the transmitting systems, the natural period of the two paths in the antenna system is equal to that of the conductively-connected closed oscillating circuits and to each of the components thereof which are included between the points x' and y' . Under such circumstances, each of the coupled receiving systems will be monoperiodic in its natural mode of vibration and will respond to electromagnetic waves of but a single definite frequency.

It will be noted that in Figs. 9, 10, 11, 12, 13 and 14, the responders are not serially connected in the closed oscillating circuits but are connected in a branch circuit across the two sides thereof, so that said oscillating circuit has a far greater persistency than would be the case if it was subjected to the damping effect of the responder resistance, and therefore a far greater resonant rise of current may be obtained in said circuit. The same is true of Figs. 18 and 19 in which the conductively-connected closed oscillating circuit is not damped by the responder resistance and in

which the larger current amplitudes, resulting in said circuit from the cumulative effect of electrical resonance due to the increased persistency of said circuit, are translated to the loosely-coupled, and therefore resonant or selective, receiving-circuit $C'_1 R I'_2$. The transformers M' may be step-up or step-down transformers according to the nature of the responder R .

In Figs. 9, 10, 11, 12, 13 and 14, large differences of potential are developed by oscillations of the proper frequency between the points of connection of the branch circuits connected across the terminals of the closed oscillating circuits which include the responders, and by such potentials, or the resulting flow of current, said responders are operated.

In Figs. 18 and 19, the primaries I'_1 of the transformers M' should preferably be wound oppositely so that said primaries will act additively or cumulatively upon the secondary I'_2 .

I have found that the capacity of the condenser C'_3 in Figs. 8, 17, 19 and 20 should be very large compared to that of condensers C' and C'_1 .

In Fig. 21, the curve represents the variation with time of the current amplitude in a closed oscillating circuit containing a spark-gap or an oscillation-responder. The oscillations are relatively non-persistent and are isochronous throughout their duration from t_0 to t_2 . Circuits of whose mode of vibration the curve shown in Fig. 21 is characteristic are, by way of example, shown by the circuit $S L C C L$ of Fig. 1 and by the circuit $C'_1 I'_2 R$ of Fig. 18.

The curve shown in Fig. 22 represents the variation with time of the current amplitude in the transmitting-circuit shown in Fig. 1 and is generally characteristic of the modes of vibration of the transmitting-circuits herein shown. The oscillations are not isochronous throughout their extent, those developed between t_0 and t_1 , when the spark-gap is conductive, consisting of a superposition of two different frequencies, neither of which is equal to that produced when the sparks cease to pass the gap S and when the oscillating system passes into the closed oscillating circuit $C' L C_3 C_3 L C$ (Fig. 1). The oscillations between t_1 and t_2 are those which are produced when the spark-gap becomes non-conducting and they are seen to be isochronous throughout their extent and to be of great persistency. The natural mode of vibration characteristic of the conductively-connected closed oscillating circuits which contain no responder in Figs. 8, 9, 10, 11, 12, 13, 14, 17 and 19 would be shown by a curve similar to that part of the curve in Fig. 22 which lies between t_1 and t_2 .

I claim—

1. In a wireless-telegraph system, an antenna system, an oscillating circuit connect-

- ed thereto and so constructed and arranged that the two paths from the top of the antenna to earth are equal in natural period, an element having relatively high dissipative resistance associated with said circuit and means for eliminating the effect of said element on the persistency of said circuit.
- 5 2. In a wireless-telegraph system, an antenna system, an oscillating circuit connected thereto and so constructed and arranged that the two paths from the top of the antenna to earth are equal in natural period, an element having relatively high dissipative resistance associated with said circuit and an auxiliary shunt-path containing a capacity connected around said element.
- 10 3. In a wireless-telegraph system, an antenna system, an oscillating circuit connected thereto and so constructed and arranged that the two paths from the top of the antenna to earth are equal in natural period, an element having relatively high dissipative resistance associated with said circuit and an auxiliary shunt-path containing a capacity connected around said element.
- 15 4. In a wireless-telegraph transmitting system, an antenna system, an oscillating system connected thereto and so constructed and arranged that the two paths from the top of the antenna to earth are equal in natural period, a spark-gap associated with said circuit and means for eliminating the effect of said spark-gap on the persistency of said circuit.
- 20 5. In a wireless-telegraph transmitting system, an antenna system, an oscillating system connected thereto and so constructed and arranged that the two paths from the top of the antenna to earth are equal in natural period, a spark-gap associated with said circuit and an auxiliary shunt-path containing a capacity connected across said spark-gap.
- 25 6. In a wireless-telegraph transmitting system, an antenna system, an oscillating system connected thereto and so constructed and arranged that the two paths from the top of the antenna to earth are equal in natural period, a spark-gap associated with said circuit and an auxiliary shunt-path containing a capacity connected across spark-gap.
- 30 7. In a wireless-telegraph receiving system, an antenna system and a closed oscillating circuit connected thereto and so constructed and arranged that the two paths from the top of said antenna to earth are equal in natural period, an oscillation-responder connected across the sides of said oscillating circuit and an auxiliary shunt-path containing a capacity connected across said spark-gap.
- 35 8. In a wireless-telegraph receiving system, an antenna system, a closed, persistently-oscillating circuit connected thereto and a circuit containing an oscillation-responder connected across the sides of said oscillating circuit.
- 40 9. In a wireless-telegraph receiving system, an antenna system, a closed oscillating circuit connected thereto and so constructed and arranged that the two paths from the top of said antenna to earth are equal in natural period, an oscillation-responder associated with said circuit and means for eliminating the effect of said responder on the persistency of said circuit.
- 45 10. In a wireless-telegraph receiving system, an antenna system, a closed oscillating circuit connected thereto and so constructed and arranged that the two paths from the top of said antenna to earth are equal in natural period, an oscillation-responder associated with said circuit and an auxiliary shunt-path containing a capacity connected across said responder.
- 50 11. In a wireless-telegraph receiving system, an antenna system, a closed oscillating circuit connected thereto and so constructed and arranged that the two paths from the top of said antenna to earth are equal in natural period, an oscillation-responder associated with said circuit and an auxiliary shunt-path containing a capacity and an inductance connected across said responder.
